M. SOCHOWITZ

WINDOW VENTILATOR

Filed Oct. 23, 1925

UNITED STATES PATENT OFFICE.

MAX SOCHOWITZ, OF DETROIT, MICHIGAN.

WINDOW VENTILATOR.

Application filed October 23, 1925. Serial No. 64,401.

My invention relates to a new and useful improvement in a window ventilator and has for its object the provision of a ventilator of this class, which will be simple in structure, economical of manufacture and highly efficient in use.

Another object of the invention is the provision of a window ventilator of this class, adapted for use with a window sash having an opening formed therein and comprising a pair of vanes radiating outwardly from a rotatably mounted supporting rod, one of the ends being imperforated and the other being perforated, so that the opening in the window sash may be opened and closed, at will.

Another object of the invention is the provision of a shield for a window sash opening of this class which will be easily attached and serve as an effective means for shedding water.

Another object of the invention is the provision of rotatable closures for the opening formed in a window shield, as described, so arranged and constructed as to be easily removable from the opening and separable from each other.

Other objects will appear hereinafter.

The invention consists in the combination and arrangement of parts hereinafter described and claimed.

The invention will be best understood from a reference to the accompanying drawings, which form a part of this specification, and in which,

Fig. 1 is a fragmentary elevational view of a window embodying the invention,

Fig. 2 is a sectional view, taken on substantially line 2-2 of Fig. 1,

Fig. 3 is a sectional view of the invention, taken on substantially 3-3 of Fig. 2,

Fig. 4 is a plan view of the screen forming member used in the invention;

Fig. 5 is a plan view of the imperforated closure forming member used in the invention.

As shown in the drawings, the invention is adapted for use with a window sash 9 having a lower rail 10 provided with an elongated opening 11. This opening is provided with a pocket 12 which is positioned at one side of the opening and in alignment with a deeper opening 13 formed in the rail

10. A rod 14 is secured to an imperforate strip 16 along the longitudinal axis thereof. The rod projects beyond the ends of the imperforated strip 16 to provide the projecting portion 17 at one side and a longer projecting portion 18 at the opposite side. Mounted on the rod 14, adjacent the projection 17, is a collar 19. As shown in Fig. 5, the strip 16 is provided, adjacent its longitudinal axis, with a longitudinally extending slot 20, which is parallel to and slightly spaced from the longitudinal axis of the strip 16. A perforate strip, or screen portion 21 is provided, which has, at one side, a slit 22, and at the opposite side, a shorter slit 23. The arrangement is such that the screen strip 21 may be inserted into the slit 20 of the strip 16 and slid longitudinally thereof to bring the strip 16 into engagement with the slit 22, this movement permitting the positioning of the screen strip 21 relatively to the strap 16, so that the strip 21 may be slid longitudinally of the strip 16, to permit the strip 16 to engage in the slit 23. The supporting rod 14 is then secured by welding, soldering, or in any other suitable manner, to the strip 16 at its longitudinal axis. The strip 16 has its edges covered with a yieldable material 24, such as leather, rubber, cloth, etc. Positioned on the longer extension 18 is a coil spring 25. The structure is such that, when assembled in the manner indicated, the projecting end 18 of the supporting rod 14 may be inserted into the recess 13, which is provided with a bushing 13'. By compressing the spring 25, the rod may then be moved, so as to permit the entry of the extending end 17 of the rod 14 to enter the opening 11 and be moved downwardly into registration with the recess 12, which is provided with a bushing 12'. The spring 25 will then serve to push the projecting end 17 into the bushing 12' and the device is thus rotatably mounted in the opening 11. When it is desired to close the opening 11, the device may be turned into the position shown in Fig. 2, the lining 24 on the member 16 serving to effect a more secure closure. When it is desired to use the device as a ventilator, the rod 14 may be rotated ninety degrees from the position shown in Fig. 2, which will serve to bring the screen

member into closing position for the opening 11.

Mounted over the opening 11 is a shield 26, having one end 27 angularly turned and seated in a recess 28 formed in the rail 10. By seating the angularly turned end in the recess 28, a seepage of water or other moisture behind the flange or angularly turned end 27 is prevented. The outer edge 10 of the shield 26 is also angularly turned as at 29 for the purpose of reenforcing, a suitable end wall 30 serving to close the opposite ends of the shield.

It is evident that the device may be easily 15 and quickly mounted in a window rail after the necessary openings and recesses have been formed. This is a desirable feature inasmuch as the parts may be quickly and easily replaced after being worn.

20 While I have illustrated and described the preferred form of structure, I do not wish to limit myself to the precise form of structure shown, but desire to avail myself of such variations and modifications as come 25 within the scope of the appended claims.

Having thus described my invention, what I claim as new and desire to secure by Letters Patent is:

1. A ventilator of the class described, 30 adapted for mounting on a window sash, comprising a rod positioned in an opening formed in the lower rail of said sash; an imperforate strip mounted on said rod and projecting diametrically outwardly therefrom at opposite sides thereof, said member being of sufficient size to close said opening; a screen member mounted on said imperforate member and projecting outwardly therefrom, in a plane other than the plane 35 of said imperforate member at opposite sides, said screen member being of sufficient size to close said opening, said rod being rotatably mounted.

2. A window ventilator of the class described, 45 adapted for mounting in an opening formed in a window sash, comprising; an imperforate member of substantially the same size as said opening; a rod secured to said imperforate member and extending longitudinally thereof, along the longitudinal axis thereof, said rod projecting at opposite ends beyond the ends of said member, said sash being provided with aligning pockets at opposite sides of said opening 50 for the reception of said projecting ends of said rod; and a perforate member of substantially the size of said opening secured along its longitudinal axis to said imperforate member at one side of said rod and lying in a plane other than the plane of said imperforate member.

3. A window ventilator of the class described, 60 adapted for use with a window rail having an opening formed therein, comprising; an imperforate member of substan-

tially the size of said opening; yieldable material covering the edges of said imperforate member; a rod secured to said imperforate member along its longitudinal axis and projecting outwardly from opposite 70 ends of said imperforate member, said rail having formed in said opening aligning recesses for receiving the projecting ends of said rod, said rod being rotatable in said recesses; a screen member secured at its 75 longitudinal axis on said imperforate member, said screen member being of substantially the same size as said opening and lying in a plane other than the plane of said imperforate member. 80

4. A ventilator of the class described, comprising an imperforate member having a longitudinally extending slit formed therein, parallel to, and spaced slightly from, the longitudinal axis thereof and terminating 85 within the marginal limits of said member, said member being of substantially the same size as said opening; yieldable material covering the edges of said imperforate member; a supporting rod extending longitudinally of and secured to said member at its longitudinal axis, said supporting rod projecting beyond the ends of said imperforate member, said opening having aligning recesses formed in opposite sides for receiving 90 said projecting ends, said supporting rod being rotatably mounted in said recesses; a perforate member having a longitudinally extending slit formed in opposite ends, one of said slits being longer than the other for 100 permitting the mounting of said perforated member in the slit formed in said imperforate member on one of the projecting ends of said rod for forcing the opposite end into its recess; and an abutment mounted on 105 said rod for limiting the thrust of said projecting end into said recess.

5. A ventilator of the class described, adapted for use with a window frame, having an opening formed therein, comprising 110 a shield extending outwardly over said opening and thence downwardly to provide a water shed, the attached edges of said shield being countersunk in said sash; and imperforate member having a longitudinally extending slit formed therein, longitudinally thereof, parallel to and spaced from its longitudinal axis, said slit terminating within the marginal limits of said member; a perforate member having a longitudinally extending slit formed in each end, said perforate member being insertable in said slit formed in said imperforate member; yieldable material secured on the edges of said imperforated member; a supporting rod 115 secured to said imperforated member at its longitudinal axis and projecting beyond the ends of the same at opposite sides, said sash having aligning recesses formed in said opening for the reception of said project- 120

125

ing ends of said rod, one of said projecting ends being shorter than the other and one of said recesses being deeper than the other; a spring mounted on the longer of said projecting ends and adapted for forcing the shorter of said projecting ends into the shallower of said recesses; and a collar

mounted on said rod for limiting the thrust of said shorter end into said recess, said rod being rotatably mounted in said recesses. ¹⁰

In testimony whereof, I have signed the foregoing.

MAX SOCHOWITZ.
